DESIGN FOR A GOBLET OR SIMILAR ARTICLE

Arthur L. Kramer, Dallas, Tex.

Application January 29, 1935, Serial No. 55,130

Term of patent 3½ years

To all whom it may concern:

Be it known that I, Arthur L. Kramer, a citizen of the United States, residing at Dallas, in the county of Dallas and State of Texas, have invented a new, original, and ornamental Design for a Goblet or Similar Article, of which the following is a specification, reference being had to the accompanying drawing, forming a part thereof.

Figure 1 is an elevation of one side of my design for a goblet; Figure 2 is an elevation of another side of my design for a goblet; and Figure 3 is a top plan view.

I claim:

The ornamental design for a goblet or similar article, as shown.

ARTHUR L. KRAMER.
